UNITED STATES PATENT OFFICE.

MATTHEW P. BENSON, OF TROY, AND MILTON M. WIENER, OF NEW YORK, N. Y.

MANUFACTURE OF BRUSHES.

Application filed April 30, 1921. Serial No. 465,873.

To all whom it may concern:

Be it known that we, MATTHEW P. BENSON and MILTON M. WIENER, citizens of the United States, residing, respectively, at 5 Troy, in the county of Rensselaer and State of New York, and New York, in the county of New York and State of New York, have invented certain new and useful Improvements in the Manufacture of Brushes, of 10 which the following is a specification.

This invention relates to the art of brush making and has particular reference to the making of brushes in which the bristles are secured with their heads within a water 15 proof body.

Among the objects of the invention is to manufacture a brush in the most economical manner, the bristles of the finished brush being of slightly varying lengths for the 20 sake of desirable penetration of the points thereof into the user's hair.

A further object of the invention is to manufacture brushes in which said penetration is accomplished, the bristles employed being cut, for the sake of economy, preferably of varying lengths but when secured in the face portion of the pad the head ends of the bristles will all be approximately in the same plane, whereby the minimum length of bristles for the purpose may 30 be practiced.

Another object of the invention is to provide a brush the pad of which is vulcanized and with the head ends of the bristles secured therein in such a manner as to present the neatest possible finished appearance and with said head ends all remote from the edge of the pad, the vulcanizing along the edge being clean and smooth.

With the foregoing and other objects in view the invention consists in the arrangement and combination of parts hereinafter described and claimed, and while the invention is not restricted to the exact details of 45 construction disclosed or suggested herein, still for the purpose of illustrating a practical embodiment thereof reference is had to the accompanying drawings, in which like reference characters designate the same 50 parts in the several views, and in which—

Figure 1 is a plan view of the brush forming devices employed during the preliminary steps, parts being broken away.

Fig. 2 is an enlarged vertical section of the same on the line 2—2. 55

Fig. 3 is a plan view, partly broken away, indicating the means employed for completing the formation of the brush pad.

Fig. 4 is a vertical section of the same on the line 4—4. 60

Fig. 5 is a vertical section of a portion of the means employed indicating the relation of the parts during the operation of filling the bristles into the face sheet of the pad.

Fig. 6 is a view corresponding to Fig. 5 65 but with the parts shifted to indicate the next step in the process.

Fig. 7 is a similar view indicating the succeeding steps.

Fig. 8 is a view of the means for completing the making of the brush pad. 70

Fig. 9 is a detail view of a portion of the brush finished and showing especially the uneven points of the bristles while the heads thereof are of approximately minimum 75 length.

Referring now more specifically to the drawings 10 is a base plate having formed therein a multiplicity of pits 11, tapered to their lower ends and shown as conical. 80 This base is provided with a plurality of dowels 12, shown as two in number, arranged near the ends of the base. Except as just described the base is preferably of uniform thickness throughout and may be 85 of any desired length and width and may be drilled or otherwise arranged for the making of any desired number of brushes at one operation.

Co-operating with the base is what may be termed a bristle receiver 13 having a multiplicity of holes 14 formed directly therethrough, each hole 14 being preferably of uniform cross section and shown as round, although the exact shape thereof is immaterial. The number of these holes and the relative position thereof correspond exactly to the number and position of the pits 11 above described, so that when the receiver is placed upon the base the holes 14 and pits 100 11 will either all register each to each or will all entirely fail to register. Compare Figs. 2 and 5. The bottom face of the receiver is drilled with two pairs of holes 15 and 15', the holes 15 being adapted in the early 105 stages of the process to receive the dowels

12 so as to hold the receiver in such position that the bottoms of the holes 14 are sealed by the flat surface of the base surrounding the pits 11, so constituting the 5 holes 14 in the form shown as closed bottomed cylinders. The receiver is fitted with a plurality of pins 16 projecting upward from the upper surface thereof a short distance. The receiver is provided also with 10 a pair of sockets 17 arranged near the periphery thereof, one socket being closer to the edge than the other, for the sake of convenience in manipulation of the device.

The next element of the apparatus is a 15 rim member 18 which may be referred to hereinafter as the holding rim, the same being provided with a large central opening 19 surrounding the field of the holes 14 and having a rabbet 20 on the lower surface adjacent to said opening. This holding rim carries also a pair of studs 21 to fit into the sockets 17 respectively to properly locate the holding rim in position on the receiver.

22 indicates a sheet of rubber or its equivalent 25 which is formed with a multiplicity of holes 23 similar in number and location to the holes 14 of the receiver and with which they register accurately each to each when the sheet 22 is impaled upon the pins 16, and 30 with the holding rim 18 put in place thereafter the edge of the sheet 22 is received within the rabbet 20 whereby the sheet is held firmly in place on top of the receiver.

A metal plate or its equivalent 24, called 35 in practice the leader, is then slipped within the opening 19 which it substantially fits, the lower surface of the leader coming flat against the top of the sheet 22. The leader is provided with a multiplicity of holes 25 40 having flaring or funnel shaped upper ends 26. These holes register with the holes 23 and 14.

With the parts assembled or arranged as 45 shown in Fig. 5 the bristles 27 are filled into the registering holes aforesaid, which may be done by any well known means, such as a sifting process, the lower ends of the bristles being guided into and through the holes 25 by the flared upper ends 26, and 50 the said lower ends or points of the bristles all come squarely against the top of the base 10. In order to provide for uneven or staggered arrangement of the bristle points in the finished brush and yet economize as to 55 the length, the bristles are cut usually in three different standard lengths as indicated in the drawings and so when the bristles are filled into the receiver as shown in Fig. 5 the head ends thereof project upward to as 60 many different elevations as there are different lengths of bristles. After the holes 23 are filled with bristles, the walls thereof having sufficient frictional engagement with the bristles, the bristles are thereby held in place 65 temporarily while the leader is removed and

the receiver together with the parts carried thereby is shifted to bring the bristles into alignment with the pits 11. To effect this shift the receiver is lifted from the dowels 12 which on entering the holes 15 accurately 70 position and hold the receiver as shown in Fig. 6. The next step in the process is to depress the bristles into the pits 11, an act performed preferably by the hand of the operator. The force thus applied to the heads of the bristles acts first upon the longest bristles insuring that they will be forced down so that their points sink deepest into the points of the pits, while those bristles of shorter length are settled or forced downward to distances proportional to their respective lengths. Thus the heads of the bristles after this operation will largely occupy the same horizontal plane at a moderate elevation above the top of the sheet 22. 80 In sifting the bristles heterogeneously into and through the receiver in connection with means to limit the points thereof in a common plane it will be understood that even though the bristles may be of varying lengths, some of the groups may be composed of shorter bristles than other groups and even in some groups the bristles may all approximate the same length, though as a rule the bristles will be suitably staggered or irregular in length in the several groups. It is essential therefore that in order to secure the proper disparity of lengths of all of the point ends of the bristles in every group 90 in the finished brush there must be a preliminary step or stage in the process of manufacture in which the points of the bristles are arranged in the same plane and then subsequently for the bristles to be moved endwise to varying distances in accordance with the final effective varying lengths of the bristles. 95 In other words, if the bristles at the stage of Fig. 5 should happen to be all of approximately the same length, by no other possible means known to us could they be rearranged 100 so as to stagger the point ends thereof for penetration except by the means or method described herein or its equivalent, because if the bristles in any group should happen to be of the same length the feature of penetration 110 would necessarily be wanting in the finished brush irrespective of which ends of the bristles in Fig. 5 become eventually the points thereof in use. Again, while as stated above in the practice of this process the bristles are as a rule collected in groups of varying lengths, it must be obvious that the longest bristles will be projected first and to the greatest extent into the tapered pits. 115 In any groups however in which the longest length of bristles may be wanting the first bristles projected downward during the shift from the step of Fig. 5 to that of Fig. 6 will enter the points of the pits and so become 120 the longest effective bristles in the finished 125 130

brush. It follows therefore that the practice of this process is not dependent in all cases upon employing bristles of varying lengths, although for greatest economy and best results we prefer to so cut them.

Now with the holding rim in place gripping the edge of the sheet 22 and surrounding the field of the bristles and with the head ends of the bristles suitably moistened a 10 plunger 28 is forced downward within the opening 19 mashing the heads of the bristles flat down upon the sheet 22. That portion of the holding rim overlapping the edge of the sheet 22 insures that none of the head 15 ends of the bristles can approach the extreme edge of the sheet any closer than provided by the preferential width of the holding rim overlap.

The plunger and holding rim are now removed, and a guide rim 29 having studs 21 is put in place of the holding rim. The guide rim has an opening 30 similar in form to the opening 19 but enough larger to receive the sheet 22, see Fig. 8, leaving the entire 25 upper surface of the sheet exposed. A binding strip 31, preferably soft rubber, is then put in place directly upon the heads of the bristles and against the upper surface of the sheet 22, the binding strip being of a size to 30 substantially fill the opening 30 and of any suitable thickness. Any suitable pressure means may be brought to bear upon the binding strip to make a permanent and water-proof joint between the binding strip 35 and the face sheet 22 and to thereby lock the bristles in the body thus formed. The preferred means of effecting this union is to employ a second sheet 32, referred to hereinafter as the backing sheet, also of rubber. A follower 33 is then applied against 40 the outer surface of the backing sheet, the follower having any suitable impression means as suggested at 34 for ornamentation or manufacturer's identification. The device is then subjected to suitable heat and 45 pressure to effect the desired union between the several sheets as above indicated, and this step ordinarily takes the form of vulcanization making the three plies of rubber, 50 22, 31 and 32, into one integral body constituting the pad of the finished brush. See Fig. 9. The impression means 34 of the follower leaves the desired mark on the finished pad as a result of the vulcanization 55 under pressure.

We claim:

1. As an improvement in the manufacture of brushes, the assemblage of bristles of different lengths in groups with the 60 points of the bristles all lying in the same plane and with the heads of the bristles lying in as many different planes as there are different lengths of bristles, then adjusting the bristles lengthwise to bring the points 65 of the longest bristles below those of shorter

length and leaving the heads of the bristles in approximately the same plane, and then securing the head portions of the bristles in permanent position, substantially as set forth.

70

2. As an improvement in the art of manufacturing brushes, the assemblage of bristles of various lengths in groups with the points of the bristles all lying in approximately the same plane, then adjusting the bristles lengthwise to cause their points to project beyond said plane to distances corresponding to the varying lengths of the bristles, and then fixing the bristles permanently in the position last stated.

80

3. As an improvement in the art of making brushes, the filling of bristles in groups in a multiplicity of holes in a bristle receiver while limiting the points of the bristles to approximately the bottom face of said receiver, frictionally holding the bristles in relation with the receiver, then forcing the bristles endwise to project the points thereof beyond said bottom face of the receiver to varying distances according to their respective lengths, and then securing the bristles permanently in the relation last mentioned.

85

4. The process of manufacturing bristle brushes as set forth in claim 3 in which the bristles are filled through the receiver against a flat surface co-operating with the receiver to hold the bristles in the initial position, the means having said surface being formed with tapered pits offset from the bristles when initially filled against said surface, and then shifting the receiver and bristles laterally to cause the bristles to aline with a multiplicity of said tapered pits.

90

5. In the making of bristle brushes, the assemblage of a plurality of bristles of varying lengths so as to initially bring their points to about the same plane while the heads of the bristles occupy different planes, then shifting the position of all of the bristles laterally, then adjusting the bristles longitudinally to cause the points of the longest of the bristles to project farther endwise than those of shorter length, then holding the bristles from endwise movement, then mashing over the head portions of the bristles at about equal lengths and into the same plane, then applying a vulcanizable material against the mashed over heads, and then securing the heads of the bristles in said plane by the vulcanization of said material.

105

6. The herein described means for making bristle brushes comprising, in combination, a receiver having holes formed therein to receive a plurality of bristles, means co-operating with the receiver to determine the distance to which the bristles will project through the receiver, a holding rim co-operating with the top of the receiver and sur-

110

115

120

125

130

rounding the field of bristle holes, said holding rim having a rabbet adjacent to said field for receiving within it a brush pad sheet, and a plunger slideable within the opening of the rim to mash down the head portions of bristles in connection with said sheet.

7. The herein described means for making bristle brushes, comprising a base having a plurality of tapered pits, a bristle receiver co-operating with the base and having a plurality of holes corresponding in number and arrangement to the aforesaid pits, means acting between the base and the receiver to hold them in two successive predetermined positions with the holes and pits first out of registry and then in registry, and means to guide bristles into said receiver holes while the holes and pits are out of registry.

8. As an improvement in the art of making brushes, the filling of bristles in groups through a multiplicity of holes in a bristle receiver while limiting the points of the bristles to approximately the bottom face of the receiver, frictionally holding the bristles in this relation with the receiver, then moving the bristles endwise to project the points thereof beyond said bottom face of the receiver to different distances therefrom so that the points of the bristles of any group will lie in different planes, and then finally securing the bristles permanently in the relation last mentioned.

In testimony whereof we affix our signatures:

MATTHEW P. BENSON.
MILTON M. WIENER.
